(57) **CLAIM**

The ornamental design for a key layout for a keyboard, as shown and described.

DESCRIPTION

FIG. 1 is a perspective view of an embodiment of a design for a key layout for a keyboard;

FIG. 2 is a top view of the embodiment of key layout shown in FIG. 1;

FIG. 3 is a bottom edge view of the embodiment of key layout shown in FIG. 1;

FIG. 4 is a left side edge view of the embodiment of key layout shown in FIG. 1; and,

FIG. 5 is a right side edge view of the embodiment of key layout shown in FIG. 1.

Broken lines are used in the drawings to illustrate environment. The features illustrated in broken lines form no part of the claimed design.
